POOL TABLE POCKET

Filed March 10, 1923

UNITED STATES PATENT OFFICE.

ANTHONY LEONE, OF GREENSBURG, PENNSYLVANIA.

POOL-TABLE POCKET.

Application filed March 10, 1923. Serial No. 624,201.

To all whom it may concern:

Be it known that I, ANTHONY LEONE, a citizen of the United States, residing at Greensburg, in the county of Westmoreland and State of Pennsylvania, have invented certain new and useful Improvements in Pool-Table Pockets, of which the following is a specification, reference being had to the accompanying drawings.

10 This invention relates to pool table pockets, and the general object of the invention is to provide means whereby the pocket may be removed from the table in a very short time.

15 A further object of the invention is to provide a pocket which may be removed from the table by simply unbuttoning the buttons which hold the pocket to the pocket iron.

20 A still further object is to so construct this pocket that it will act in all respects like an ordinary pocket but at the same time is readily removable without the necessity of removing a large number of bolts, which is necessary at the present time.

Other objects will appear in the course of the following description.

My invention is illustrated in the accompanying drawings, wherein:

30 Figure 1 is a top plan view of one corner of a pool table with my pocket applied thereto;

Figure 2 is a top plan view of the pocket iron;

35 Figure 3 is a sectional view on the line 3—3 of Figure 1;

Figure 4 is a fragmentary longitudinal sectional view of the leather casing and allied parts applied to a portion of the table iron;

40 Figure 5 is a perspective view of one end of the leather casing;

Figure 6 is a fragmentary sectional view taken on the same plane as Figure 3 but showing a modification in the means for holding the flanges 15 and 16 closed upon the pocket.

45 Referring to these drawings, it will be seen that 10 designates the ordinary pocket iron, this pocket iron being approximately semi-circular in plan with somewhat tangentially extending terminals 11, circular in cross section, and each having an aperture 12 extending vertically downward through this extension of the iron.

50 As shown in Figure 2, the iron is nar-

rower at its middle than at the ends of the semi-circle, where it is relatively broad, and the broadened end terminates in a shoulder 13 which intersects the corresponding pin or extension 11. The top face of the iron is transversely flat at the ends but the middle of the iron curves outward and downward to the under face. The under face of the iron extends upward and forward to the inner edge face, which is relatively thin. So far I have described an iron of ordinary character and my invention does not relate thereto.

55 Adapted to extend over and encase this iron is a leather casing, designated generally 14. This is formed of a single thickness of leather which is shaped to fit the iron and to provide a downwardly extending, inner, marginal portion 15 and a downwardly extending, outer, marginal portion 16. These marginal portions 15 and 16 are disposed immediately opposite each other and the leather casing is so formed that the leather casing extends inward under the under face of the iron 10 so as to bring the two longitudinally curved marginal portions into approximate concentricity to each other and in approximate contact. The outer flange or marginal portion 16 is formed with a series of sockets 17, each of these sockets being headed, as at 18, upon the outer surface of the flange 16, and the flange 15 of the leather casing is provided upon its inner surface with a series of inwardly projecting, elastic studs 19 adapted to be inserted into the sockets 17 and having engagement therewith. In other words, the sockets 17 and the studs 19 are formed by ordinary snap fasteners of a relatively large size.

60 The ends of the casing 14 extend downward, as at 20, over the end faces 13 of the iron 10 and are cut away, as at 21, to surround the bases of the extensions 11. Attached to the inner face of the flange 15 is a leather skirt 22 whose lower margin is scalloped along its lower edge. This leather or leatheroid material has its upper margin folded and stitches 23 hold this skirt to the flange 15. The flange 16 is also provided with a skirt 24 of leatheroid or like imitation leather material, the upper edge of which is inwardly turned, and this skirt along its upper edge is stitched to the flange 16.

65 As before remarked, the casing 14 is

formed and shaped so that it has permanently the general form of the iron 10. The pocket, which is of the usual reticulated material and which is designated 25, has 5 attached to one margin thereof and for approximately half of the diameter of the pocket a band 26 which may be made of leather, leatheroid, fiber or any other suitable material, this band being composed of 10 two superposed thicknesses stitched together around the margins of the thicknesses and stitched to the net work pocket 25. This band adjacent its upper margin is provided with a plurality of openings 27 15 through which the studs 19 are adapted to pass. The free portion of the upper margin of the reticulated pocket 25 is adapted to be connected to the body of the table by any suitable means as, for instance, by large 20 headed tacks or by retaining plates. The means whereby this portion of the pocket is retained against the table forms no part of my present invention.

In the use of this device, the casing 14 is 25 disposed to surround and encase the iron 10, as illustrated in Figure 3, and the band 26 is disposed between the flanges 15 and 16. The studs 19 pass through the apertures 27 of the band and into the sockets 17, thus 30 holding the band and the pocket in proper engagement with the casing 14 of the iron 10. When it is desired to remove the pocket in order to replace it by a new pocket, it is only necessary to pull outward 35 upon the flange 16, thus detaching the snap fastener members from engagement with each other, and when this has been done the band 26 may be pulled off of the studs 19 or will slip therefrom and a new pocket 40 may be put in position with its band between the flanges 15 and 16 and then these flanges forced together, causing the snap fasteners to engage. The free portion of 45 the pocket may be then attached to the under face of the table in any suitable manner.

Ordinarily in removing a pocket from a table as ordinarily constructed, some ten bolts have to be removed and the iron frame 50 or pocket iron removed so that it takes about a half hour to remove a pocket. With my construction, the pocket may be removed and a new pocket attached in but a few minutes and this without removing the iron 55 and without removing any bolts.

While I have illustrated an embodiment 60 of my invention which I have found to be thoroughly effective and which is very simple, I do not wish to be limited thereto, as it is obvious that the details of construction 65 might be varied without departing from the spirit of the invention as embodied in the appended claims.

Thus, for instance, in Figure 6 I have shown a modified form of means for holding 65 the flanges 15 and 16 in engagement with the pocket, this modification consisting in the use of a fastening device formed in two sections which have engagement with each other by coacting threads. This fastening 70 device comprises the socket member 17^a having a socket which is interiorly screw-threaded and the stud member 19^a which has a stud which is exteriorly screw-threaded to fit within the socket member. This construction permits the holding device or fastening device to be removed and re-used when it becomes necessary to put on a new pocket, 75 whereas with the construction illustrated in Figures 3 and 4, for instance, the metal buttons or snap fasteners can be no longer used when the pocket is thrown away. This reduces the cost of production of the pocket, as the button will be removed from the old pocket when the pocket is worn out and 80 put into the new pocket.

I claim:—

1. A pool table pocket including a pocket iron, a casing enclosing and fitting the pocket iron and formed to provide opposite 90 depending margins having coacting fastening members and the pocket proper having a marginal band insertible between the margins of the casing and having apertures through which the snap fastener members 95 engage.

2. A pool table pocket including a semi-circular pocket iron, a leather casing approximately semi-circular in plan and enclosing and fitting the pocket iron and 100 formed to provide opposed depending margins having coacting snap fastener members, skirts attached to the outer faces of said margins and depending below the same, and a pocket proper having a marginal band 105 insertible between the margins and having apertures through which the snap fasteners engage.

3. A pool table pocket including a curved pocket iron, a leather casing enclosing and 110 fitting the pocket iron and formed to provide opposed depending margins extending the length of the curved portion of the pocket iron, the outer flange carrying a series of open sockets and the inner flange 115 having a series of inwardly projecting, coacting studs insertible into the sockets, and a pocket having a marginal band attached to the pocket along a portion of its margin and adapted to be disposed between said margins 120 of the casing, the marginal band having apertures through which the studs pass.

In testimony whereof I hereunto affix my signature.

ANTHONY LEONE.
